BRONZING APPARATUS

Arthur Bell, London N.1, England, assignor to
American Machine & Foundry Company, New
York, N. Y.

Application September 24, 1942, Serial No. 459,597
In Great Britain October 8, 1941

4 Claims. (Cl. 91—16)

This invention relates to bronzing means for use in connection with the bronzing (or similar treatment) of imprints on cigarettes and more particularly to cigarette machine printers of the single drum type, i. e. wherein the cigarette paper web passes around a single drum about which is located the die or dies of the printer and the bronze applying and cleaning means.

An object of the invention is to provide improved means for applying bronze to the imprints whereby the bronze is brought into contact only with those parts of the wrapper or web where the imprints are located instead of being brushed over the whole surface as hitherto. A further object is to provide improved means for removing and collecting the excess bronze from the paper web in a manner adapted to recover a high percentage of the bronze.

According to one feature of the invention the removal of the excess bronze is effected by one or more rotary brushing rolls.

According to another feature of the invention excess bronze is removed by brushing means located in a chamber which is coupled to a source of suction.

According to a further feature of the invention the bronze is applied to the imprint by a rotary element having a segmental bronze applying surface and driven synchronously with the printer die roll, whereby the bronze is only brought into contact with the cigarette web at the spaced imprints.

The invention will now be described with reference to the accompanying drawings, in which:

Figure 1 is a front view of the bronzing apparatus, the front cover of the housing for the bronze applying and cleaning mechanisms being omitted;

Figure 2 is a section on line 2—2 of Figure 1, the front cover of the housing for the bronze applying and cleaning mechanisms being shown fragmentarily;

Figure 3 is a detail section of the bronze applicer, and

Figure 4 is a section of a modified bronze applicer.

In carrying the invention into effect according to one convenient mode as applied to a cigarette printer having a single drum 1 and a pair of printing assemblies arranged at spaced points, 2, 3, the drum surface 4 passes through a pair of chambers 5, 6 formed in a housing 43 and located between the printing assemblies, one chamber 5 accommodating bronze applying means, while the other chamber 6 accommodates

bronze cleaning means. Printer die roll 2 applies spaced imprints of sizing material to the cigarette paper running over drum 1, and the bronze applying means applies bronze to the spaced imprints of sizing material on the cigarette paper. The printer die roll 3 applies ink of the desired color to the bronzed sections of the cigarette paper. Since the construction and operation of the die rolls 2 and 3 is conventional, further description thereof is deemed unnecessary.

The bronze cleaning means comprises a pair of spaced driven rolls 7, 8 having a brushing surface 9 conveniently formed of a strip of plush or other suitable pile fabric or it may comprise hair or bristles. The brushes co-operate with stationary rods 31 to prevent clogging with the bronze. The rods 31 are mounted in brackets 32 which are provided with oval slots through which pass screws 33 threaded into shafts 34 and supporting brackets 32. On bushings 35 on shafts 34 are mounted gears 13 and 14, and the rolls 7 and 8 are fixed to the hubs of gears 13 and 14, respectively. The shafts 34 are supported by adjustable arms 10, 11 pivoted coaxially with a common driving gear wheel 12 meshing with gears 13, 14, the arms 10 and 11 being respectively provided with extensions 10a and 11a. The gear 12 is secured to a shaft 37 revolving in a bushing 39 on which the arms 10 and 11 are pivotally mounted, bushing 39 being supported in a boss 41 of the housing 43. The common gear wheel 12 is driven from any suitable moving part on the machine, as hereinafter described. Means are provided for setting and locking the arms 10, 11 in their adjusted positions. Such means may comprise adjusting spindles 15 and 16 threaded into the portion of the front cover 43a which is fragmentarily shown in Fig. 2, and provided with eccentric portions 15a and 16a respectively, adjacent their inner ends and operable by knobs 17, 18 from the exterior of the chamber 6. The inner ends of the spindles 15 and 16 are supported in the housing 43. The eccentric portions 15a and 16a of spindles 15 and 16 bear against the extensions 10a and 11a of arms 10 and 11 which are held in contact with the eccentric portions 15a and 16a by tension springs 19, 20. When set the arms may be locked by a stud 30 passing through transverse slots in extensions 10a and 11a, shown in dotted lines in Fig. 1, and threaded into housing 43 (Figs. 1 and 2), the stud 30 being provided on its outer end with a nut 30a engaging the extension 10a and clamping the extensions 10a and 55 11a against a shoulder 30b on stud 30.

The chamber in which the brushing rolls 7 and 8 are located is connected up to a suitable source of suction by way of a nipple 45 in which the hose 29 is secured and a separation chamber (not shown) whereby the excess bronze removed by the rolls is collected for returning to the bronzing compartment. Nipple 45 is retained against the bottom of housing 43 by blocks 47 fastened to the bottom of housing 43, and one end of hose 29 is secured in a collar 49 fastened to the bottom of nipple 45.

By using cleaning rolls such as 7, 8 instead of the usual velvet band it is found that the recovered bronze is substantially pure whereas with the band a considerable amount of chalk and other foreign matter is removed from the cigarette web and becomes mixed with the bronze. It will moreover be appreciated that with the known velvet band (apart from the fact that it acts with a rubbing action) owing to its considerable contact area with the paper web, picks up surplus bronze, chalk and other foreign matter and in a comparatively short time becomes so impregnated that it ceases to be a cleaning device. On the other hand, with the improved arrangement of brushing rolls which only have line contact with the cigarette web, these disadvantages are eliminated so that they retain their cleaning properties for a much longer period.

While it is preferred to use a pair of brushing rolls 7, 8 in some circumstances one roll may be adequate or more than two rolls may be used.

According to a modification the suction effect may be confined to the zone of the brush rolls by the provision of a pair of shields partially surrounding the brush rolls and secured upon a manifold coupled up to a source of suction.

In applying the bronze according to the invention a rotary roll 21 is provided having a wiper 22 (or wipers) of velvet or other suitable material connected to the roll by suitable clipping means 23, the free or loose portion of the wiper 22 being of a length only sufficient for the imprint so that the bronze is only applied upon the surface of the cigarette web at the spaced imprints. Roll 21 is secured on one end of a shaft 55 supported in a boss 57 of housing 43 (Fig. 3). A gear 59 keyed on the other end of shaft 55 is driven through an intermediate gear (not shown) from the die roll 2. A pinion 61 is secured to the hub of gear 63 keyed on the end of the shaft 37 protruding from the boss 41 of housing 43. Gear 63 is driven from a suitable gear (not shown), and gear 61 drives the printer die roll 3 through intermediate gears (not shown).

The gear 59 on the shaft 55 of roll 21 is driven in synchronism with the printer die roll 2 by suitable change gear wheels according to the speed of the die roll so that the bronze is applied at the appropriate positions.

The bronze is conveyed to the wiper roll 21 by

a feeder roll 24 which is located in the bronze supply, a concentric oscillating agitator 25 being provided which is oscillated by a cam 26 engaging arms 27 on the agitator.

5 According to a modified form of bronze applying roll (see Figure 4), a strip of adhesive felt or velvet 28 is anchored to the roll 21, the strip being secured to the top of the clip by the adhesive to form a pad or dabber.

10 I claim:

1. In a cigarette machine printer, the combination with a rotating member for imprinting uniformly spaced sections of a continuous web of cigarette paper, of a rotary roll having a segmental bronze applying surface and driven synchronously with said member to apply bronze only to the spaced imprints of said web, and a rotary brushing roll arranged to engage said web and brush off surplus bronze applied to said imprinted sections.

15 2. In a cigarette machine printer, the combination with a rotating member for imprinting uniformly spaced sections of a continuous web of cigarette paper, of a rotary roll having a segmental bronze applying surface and driven synchronously with said member to apply bronze only to the spaced imprints of said web, and a rotary brushing roll arranged to engage said web and brush off surplus bronze applied to said imprinted sections, and a suction hood surrounding said roll and connected to a suitable source of suction.

20 3. In a cigarette machine printer, the combination with a device for imprinting uniformly spaced sections of a continuous web of cigarette paper, of means for applying bronze only to the imprinted sections of said web, a pair of rotating rolls which are each covered with plush and arranged to engage said web and brush off surplus bronze applied to said imprinted web sections 35 by said device, a pair of pivoted arms each supporting one of said rolls, and mechanism for adjusting said arms to move said rolls toward or away from said web.

25 4. In a cigarette machine printer, the combination with a device for imprinting uniformly spaced sections of a continuous web of cigarette paper, of means for applying bronze only to the imprinted sections of said web, a pair of rotating rolls which are each covered with plush and arranged to engage said web and brush off surplus bronze applied to said imprinted web sections by said device, a pair of pivoted arms each supporting one of said rolls, and mechanism for adjusting said arms to move said rolls toward or away from said web, said mechanism comprising 30 55 a pair of rotatable spindles, eccentrics mounted on each of said spindles and respectively engaging one of said arms, and springs urging said arms against said eccentrics, whereby rotation of said spindles will vary the position of said rolls with respect to said web.

ARTHUR BELL.
